UNITED STATES PATENT OFFICE.

ARTHUR G. HATCH, OF DULUTH, MINNESOTA.

BUILDING CONSTRUCTION.

1,408,734.

Specification of Letters Patent. Patented Mar. 7, 1922.

Application filed January 14, 1921. Serial No. 437,274.

To all whom it may concern:

Be it known that I, ARTHUR G. HATCH, a citizen of the United States, residing at Duluth, in the county of St. Louis and State of Minnesota, have invented certain new and useful Improvements in Building Construction, of which the following is a specification.

This invention relates to a new and improved building construction, and more particularly to a wall construction comprising a plurality of separate wall elements.

In building construction the building wall should keep out moisture and cold and retain the warmth of the building itself, and further should be adapted not to transmit sound. These characteristics are best secured by providing a wall having insulated air spaces. It is highly desirable that this air space be so formed as to prevent ready passage of air currents. It is a well-known principle that where air currents tend to pass through a restricted area and then through enlarged spaces, the air itself builds up secondary air currents which retard its passage. Due to this fact the air spaces may be continuous and yet be so formed as to prevent free passage of the air with its consequent heating or cooling effect.

It is an object of the present invention to provide new and improved wall structure which is composed of a plurality of walls each comprising a multiplicity of block elements.

It is a further object to provide a structure of this character which is capable of a variety of methods of assembly.

It is an additional object to provide a structure which is composed of but few forms of elements, the various elements being interchangeable and of shapes which may be readily constructed and handled.

Other and further objects will appear as the description proceeds.

I have illustrated certain preferred embodiments of my invention in the accompanying drawings, in which—

Figure 1 is a fragmentary section illustrating my improved wall construction with associated floor constructions;

Figure 2 is a face view of the preferred form of wall block;

Figure 3 is a longitudinal section of Figure 2;

Figure 4 is a cross section of Figure 2;

Figure 5 is a fragmentary face view, partly broken away, showing the form of construction of Figure 1.

Figure 6 is a fragmentary face view illustrating another form of construction;

Figure 7 is a horizontal section taken on line 7—7 of Figure 6, and;

Figure 8 is a section taken on line 8—8 of Figure 7.

Referring first to the form of wall shown in Figure 1, the outer wall at the left of the figure comprises a plurality of blocks of the type shown in Figures 2, 3 and 4. These blocks each comprise a face wall 20, upper and lower flanges 21, and end flanges 22 and a transverse septum 23. As best shown in Figure 4, the upper and lower flanges 21 are formed with straight inner surfaces sloping inwardly in such manner that the flanges increase in thickness toward their junction with the wall 20. The end flanges 22 are formed upon an arc of a circle, the center of curvature being preferably located substantially at the junction of the front and end faces. This particular curvature greatly facilitates the removal of the blocks from the mold. The blocks may be formed with a continuous groove 24 extending around the face of the flanges. This groove is adapted to receive bonding mortar or to receive reinforcing rods.

In the form of wall shown in Figure 1, two separate walls are built up with blocks of the type shown in Figures 2 to 4, the blocks being oppositely faced to bring their flanges toward each other. In the drawing the wall rests upon the foundation 25, a special block 26 being placed directly upon the foundations. This block is provided with an inwardly facing shoulder 27. The floor 28 rests both upon the foundation 25 and the shoulder 27. The surface between the floor slab and the block 26 is preferably coated with tar or with a sheet of tarred paper in order to prevent transmission of moisture from the outer face of the wall to the floor, or vice versa.

The weep pipe 29 passes down through the floor and foundation from the intermediate cavity in the wall and is adapted to carry off any moisture which may form within the wall. The oppositely faced blocks 30 rest upon the floor and the special blocks as shown. Subsequent floors are formed as was the floor 28, with the exception that the floor rests directly upon the

inner wall and part of its load is transmitted to the outer wall by the special block 26'. The floor is provided with a weep pipe 32 to permit passage of moisture. The 5 binding elements 38 used in this form of wall are clearly shown in Figures 1 and 5. These bonding elements are blocks extending transversely between the two separated walls and as shown in the figures, the blocks 10 are placed in staggered relation so that the air space is not interrupted at any point. They are inserted by breaking away the upper and lower flanges of the blocks 30 at the points at which the bond block is placed, 15 the bond block thus resting upon the flanges of the blocks of the lower course and being tied by mortar also to the flanges of the course above. Obviously the wall may be made of any desired width by increasing 20 the distance between the separated walls and similarly increasing the length of the bond blocks.

In Figures 6 to 8 a special type of wall block 41 is shown having the face flange 25 extending at 42 beyond the end flange 43 and the upper and lower flanges 44. This affords a concealed bond, as shown in Figure 7, in which it is unnecessary to break away any of the face block flanges. The bond 30 blocks 45 are located at the junction of adjacent face blocks and interfit between the adjacent end flanges 43. They extend across only to the plane of the flanges of the opposite wall, as shown in Figure 16, and are 35 connected to the bond blocks above and below them by mortar.

Obviously either of the forms of walls shown may be made of any practical width simply by the use of longer bond blocks.

These walls have the advantage that they are 40 made of standard forms of block which greatly minimizes the stock it is necessary to provide for the construction thereof, and also cuts down the work necessary. The 45 walls afford an air space which is continuous and yet so provided with narrowed portions that the air movement is reduced to a minimum. The insulation afforded by the wall is therefore very effective. The 50 special block for the floor-receiving portions of the wall serves to transfer the floor load properly to both outer and inner face walls. The method of construction is exceedingly 55 simple and can be carried out at small cost. It may be accomplished with relatively inexperienced labor and at considerable speed.

I claim:

1. Wall construction comprising oppositely faced blocks, the blocks having substantially plane outer faces and flanges extending inwardly from the inner faces, and transversely extending bonding blocks connecting the oppositely faced blocks, the flanges having recessed portions whereby the bonding blocks extend within the flange 60 contour.

2. Wall construction comprising oppositely faced blocks, the blocks having substantially plane outer faces and flanges extending inwardly from the inner faces, and 70 transversely extending bonding blocks connecting the oppositely faced blocks, portions of the flanges being broken away to receive the bonding blocks.

Signed at Duluth, Minnesota, this 6th day 75 of January, 1921.

ARTHUR G. HATCH.
